UNITED STATES PATENT OFFICE.

JOSEPH R. BOWLING, OF ST. LOUIS, MISSOURI, ASSIGNOR TO THE INGOLDSBY AUTOMATIC CAR COMPANY, OF ST. LOUIS, MISSOURI, A CORPORATION OF WEST VIRGINIA.

DUMP-CAR.

1,026,785.

Specification of Letters Patent.

Patented May 21, 1912.

Application filed November 14, 1907. Serial No. 402,181.

To all whom it may concern:

Be it known that I, JOSEPH R. BOWLING, a citizen of the United States, residing in St. Louis and State of Missouri, have invented 5 a certain new and useful Improvement in Dump-Cars, of which the following is a full, clear, and exact description, reference being had to the accompanying drawings.

The object of this invention is to provide 10 a dump car having a plurality of doors with means for releasing any door or doors at will, the remaining door or doors continuing locked.

The invention, though not so limited, is 15 well adapted for cars having dumping doors forming a portion of the load-carrying floor, such doors being supported by hooks carried by the sides of the car which engage floor beams projecting from the 20 door. The invention is herein shown as applied to a transverse dumping car of the type shown in application No. 397,900 of Frank S. Ingoldsby, wherein the doors are transverse and are provided near their 25 meeting edges with projecting floor beams which the hooks on the sides of the car engage. In the present illustration I have shown three pairs of such dumping doors.

The invention consists broadly of door- 30 locking mechanism adapted to release any of a plurality of doors, and, more particularly, such invention as applied to cars having side supporting hooks.

The invention is hereinafter more fully 35 described and its essential characteristics set out in the claims.

In the drawings, Figure 1 is a side elevation of a car having my invention applied thereto; Figs. 2 and 3 are perspective views 40 of the upper end of a supporting hook and the operating link, showing the same in two positions; Fig. 4 is a perspective view of the pin for locking the hook either to the operating link or the stationary bracket.

45 Referring to the drawings by reference numerals, 10 represents the car side, which is shown as a plate girder having on the upper chord 11, the lower chord 12 and vertical stiffeners 13.

50 14 represent the dumping doors, of which three pairs are shown, these doors being mounted on transversely arranged hinges 15.

16, in dotted lines, represents inclined end floors leading to the endmost doors and 17 55 indicates transverse shedding beams between intermediate doors.

Each door is shown as provided near its free edge with a floor beam 20 which braces and stiffens that edge and extends beyond the car side for engagement with supporting and locking levers or hooks. These hooks, designated 21, are pivoted to the side of the car in a suitable manner and have their upper ends connected by links with a main operating lever 23. It is to be understood that the same system of levers and links is provided on the opposite side of the car. The operating lever, however, is preferably employed only on one side of the car, while on the other side there is an arm 70 similar to the portion of the operating lever between the link and the pivot, this arm being connected with the operating lever by a transverse rock shaft rigid with both of them. 75

The above described car is shown and claimed in the application referred to. That application also shows and claims means for raising the doors to closed position. Any suitable raising mechanism may be 80 associated with my invention.

To enable any of the pairs of doors shown to be released independently of the others, (or the independent release of single doors, where single doors are employed) I provide the peculiar connection between the hooks and their operating links which is the gist of the present invention and will now be described. As shown at 25 each lever or hook is forked at its upper end. 85 The operating links 26 and 27 (connected with the lever 23 by a link 24) lie within these forks. Suitable bolts, rivets or other pins 28 carried by the levers project through slots 29 in the links. These pins 28 normally stand at the end of the slot most distant from the operating lever. 90

30 indicate pins which are adapted to extend through holes 31 in the links on the other side of these levers, this construction 100 acting to practically pivot the levers to the links, so that these levers may be operated in the usual manner by throwing the main lever.

Above each lever 21, and secured to the 105 side of the car, is a stationary bracket 35, and the upper end of the lever is bent laterally as at 36 to stand beneath this bracket. The bracket and the lateral bend in the lever are each provided with holes 37—38. Now 110 if the pin 30 be removed from the link, and instead be passed through the bracket and

upper end of the lever, the result is that the lever remains locked while the link is freed from the lever and may thus operate the other levers independently. The slot 29 allows the link movement to swing the engaged levers sufficiently to release the doors.

It will be seen that the levers for any of the pairs of doors may be locked, allowing the main lever to release the other two. 10 Thus in the embodiment shown any pair of doors may be dumped leaving the other two pairs locked, or any two pairs may be dumped (the two nearest either end, or the two extreme pairs) leaving the other pair 15 locked, or all three pairs may be dumped at once. To enable this universal independence of operation the link 27 to the far pair of doors is connected by a knuckle 39 with the link 26. The link 24 connecting the 20 link 26 with the operating lever also has a jointed connection.

It is to be noticed that on the closing movement the ends of the slots 29 come into positive engagement with pins 28 on the 25 levers 21, so that any of these levers which may be thrown forward when the doors are dumped are certain to be brought back to their locked position when the links are returned to their normal locked position. 30 This is a valuable feature, for it insures all the doors being locked when the main lever is in place and prevents any discharge of any section of the load without destroying the seal which holds the main lever.

35 To hold the pin 30 in place in either position, it is preferably provided with a tongue 41 which is adapted to pass through a corresponding recess 42 in the sides of the openings 31, 37 and 38. The pin is shown 40 as bent at right angles, so that the weight of its end 44 when it is in the link automatically swings it by gravity into position where the tongue passes behind the groove and so holds it against displacement. The 45 end of this bent portion is provided with an eye 46 by which it may be connected by chain 47 with a suitable point as the bracket 35. This chain is loose enough to allow all the required movement of the link and lever. 50 When the pin 30 is in place in the bracket 35 for holding the hook stationary, the weight of the chain keeps it in position, so that the tongue is out of alinement with the groove 42. The eye 46 may also furnish 55 convenient means for the passage of a sealing wire or band into the opening 48 in the bracket 35 in which the chain is anchored, or into the slot in the link as the case may be, thus preventing any undetected tampering 60 ing with the load.

I have shown the releasing mechanism as applied to a transverse dump car. It is to be understood, however, it is equally adaptable to cars of the standard Ingoldsby type 65 having a central longitudinal member and

longitudinal doors hinged thereto, and having projecting floor beams with which the hooks engage. The invention is of use wherever there are a plurality of doors which it is desired to release in universal 70 independence.

I claim:

1. In a dump car, the combination of a plurality of dumping doors on the same side of the car, and means operated by the 75 same mechanism for releasing any of them without affecting the other, as desired.

2. In a dump car, the combination of a plurality of dumping doors, locking means, and means for releasing either door while 80 the remaining door or doors are locked, said last mentioned means being actuated by the same mechanism for any door.

3. In a dump car, the combination of a plurality of dumping doors, locking means, 85 common operating means therefor, and means for releasing either door while the remaining door or doors are locked, said last mentioned means being actuated by the same mechanism for any door. 90

4. In a dump car, the combination of a plurality of dumping doors, supporting means carried by the side of the car, and means actuated by the same mechanism for all doors for causing the supporting means 95 to release any of the doors as desired.

5. The combination, with the car sides, of dumping doors forming a portion of the load carrying floor, floor beams carried by the doors extending beyond the car sides, 100 means on the car sides for engaging and supporting said beams, said means being independent for the different doors, mechanism for independently locking said means, and common operating mechanism for said 105 means when unlocked.

6. The combination with the car sides of dumping doors forming a portion of the load carrying floor, floor beams carried by the doors extending beyond the car sides, hooks on the car sides for engaging and supporting said beams, mechanism for independently locking said hook, and common operating mechanism for said hooks 110 when unlocked. 115

7. In a dump car, the combination of dumping doors, floor beams carried thereby, hooks carried by the sides of the car and adapted to engage such floor beams to support the doors in closed position, links for operating such hooks, and means to connect or disconnect such links from the hooks as desired. 120

8. In a dump car, the combination of dumping doors, floor beams carried thereby, hooks carried by the sides of the car and adapted to engage such floor beams to support the doors in closed position, links for operating such hooks, stationary brackets, and means to disconnect such hooks from 125 130

the links and connect them with the stationary brackets or vice versa.

9. In a dump car, the combination of dumping doors, hooks carried by the sides of the car and adapted to support the doors in closed position, links for operating such hooks, means to connect or disconnect such links from the hooks as desired, said means comprising slots in the links, and means for 10 restricting the freedom provided by the slot.

10. In a dump car, the combination of dumping doors, floor beams carried thereby, hooks carried by the sides of the car and adapted to engage such floor beams to support the doors in closed position, links for operating such hooks, means to connect or disconnect such links from the hooks as desired, said means comprising slots in the links, means carried by the hooks projecting through the slots, and means for 20 restricting the freedom provided by the slot.

11. In a dump car, the combination of dumping doors, pivoted locking hooks, stationary brackets, an operating link, and means adapted to connect the hooks with either the stationary brackets or the operating link.

12. In a dump car, the combination of dumping doors, pivoted locking hooks, stationary brackets, an operating link, and pins adapted to connect the hooks with either the stationary brackets or the operating link, the link being slotted to allow free movement when disconnected.

13. In a dump car, the combination of a car side, hooks pivoted thereto, dumping doors adapted to be supported by said hooks, said hooks being forked at their upper ends, operating links lying in said forks, 30 said links being slotted, pins carried by the forks and passing through said slots, and pins adapted to be passed through the links adjacent to the ends of the hooks.

14. In a dump car, the combination of a car side, hooks pivoted thereto, dumping doors adapted to be supported by said hooks, said hooks being forked at their upper ends, operating links lying in said forks, 45 said links being slotted, pins carried by the forks and passing through said slots, the upper ends of the hooks being bent laterally, stationary brackets above such lateral bends, and pins adapted to be passed through the bracket and bent ends, or 55 through the links adjacent to the ends of the hooks.

15. In a dump car, the combination of dumping doors, supporting hooks, an operating link, and a pin adapted to make effective connection between the hooks and link, said pin having a tongue on one side and the opening which the pin occupies having a corresponding recess.

16. In a dump car, the combination of 65 dumping doors, supporting hooks, an oper-

ating link, and a pin adapted to make effective connection between the hooks and link, said pin being bent and provided with an eye.

17. In a dump car, the combination with 70 the car side and dumping doors of supporting hooks pivoted to the car side, brackets carried by the car side, means adapted to hold the hooks to the brackets, and means for operating the hooks when released from their brackets.

18. In a dump car, the combination, with 80 the car side and dumping doors of supporting hooks pivoted to the car side and having lateral projections at their upper ends, brackets carried by the car side and adapted to stand above such projections, pins adapted to pass through the brackets and projections, and means for operating the hooks when released from their brackets.

19. In a dump car, the combination of a plurality of load supporting doors, independent means for holding the various doors, common means for throwing the several holding means, and means for disengaging 90 said common means from the holding means, and for locking the holding means.

20. In a dump car, the combination of a 95 plurality of load supporting doors, independent means for holding the various doors, common means for throwing the several holding means, means for disengaging such common means from the holding means, and means whereby such disengagement does not prevent the common means 100 from returning the holding means to locked position.

21. In a dump car, the combination of a plurality of load supporting doors, independent means for holding the various doors, common means for throwing the several holding means, means for disengaging said common means from the holding means, means for locking the holding means, and means 105 whereby the return of the throwing means may insure all of the holding means being brought to closed position.

22. In a dump car, the combination of a plurality of dumping doors on the same 110 side of the car, locking means, common operating mechanism for all of said locking means, and means for releasing either door while the remaining door or doors are locked.

23. In a dump car, the combination with 115 a plurality of load supporting doors, of means for independently releasing the doors, means for locking the doors not released, and a common positive means for concurrently releasing the various doors or a selection of them.

24. In a car having a plurality of doors on each side, means for opening any one of the doors independently of any of the others 120

- when they are loaded, and means for locking the door or doors not opened.
25. A car provided with a plurality of doors on each side thereof, adapted to be opened and closed, in combination with means for opening any one of the doors independently of all the others, and means for locking the door or doors not opened.
26. In a car having a plurality of doors on each side, means for concurrently opening any one or more of the doors independently of all the others, and means for locking the doors not opened.
27. In a car provided with a plurality of doors on each side thereof, means for holding them closed, in combination with means for opening any one or more of the doors independently of all the others, and means for locking the doors not opened.
28. A vehicle provided with a plurality of swinging floor sections located along one side and adapted to be depressed independently of each other, mechanism for independently maintaining the floor sections in closed position, means for locking the individual parts of said mechanism, and mechanism acting simultaneously upon the aforesaid mechanism to permit said floor sections to descend.
29. A vehicle provided with a plurality of swinging floor sections located along one side and adapted to be depressed independently of each other by the load portions carried thereby, mechanism for maintaining the floor sections in closed position, means for locking the individual floor sections, and mechanism acting simultaneously upon the aforesaid mechanism to permit the unlocked floor sections to descend.
30. A vehicle having a plurality of swinging floor sections located along one of its sides, each floor section being adapted to be depressed independently of the other, means for individually locking said floor sections, and mechanism serving to permit the load portions carried by said floor sections to permit a depression of the said sections which are not locked simultaneously.
31. In a vehicle, the combination with a plurality of swinging floor sections located at one side thereof and adapted to be depressed independently of each other, of mechanism for maintaining and locking the said floor sections in closed positions, and mechanism acting at the same time upon the first mentioned mechanism to permit said floor sections to descend, said floor sections having their free ends adjacent to a side of the vehicle.
32. In a vehicle, the combination with a plurality of swinging floor sections located along one side thereof, each of the said floor
- sections being adapted to be depressed independently of the others, means for holding the said floor sections in closed position, and means for individually locking the means just mentioned, and mechanism acting at the same time upon the aforesaid floor sections, maintaining means, to permit said floor sections to descend, said floor sections having their free ends adjacent to a side of the vehicle.
33. In a dump car, the combination with a plurality of doors upon the same side of the car, dumping mechanism therefor, whereby such dumping mechanism may release either one door or a plurality of doors concurrently, and means for locking the doors not released.
34. In a dump car, the combination of a plurality of dumping doors on the same side of the car, means for releasing the doors together or releasing one independently, means for locking the doors not released before the release of the other doors takes place.
35. In a dump car, a plurality of doors, other supporting devices carried upon the sides of the car, a common means for operating the said doors to release the same, means for connecting the individual door supporting devices with the said operating means, and means for locking the door supporting devices not connected to the operating means.
36. In a dump car, the combination of a plurality of dumping doors, a plurality of movable supporting members therefor, operating mechanism adapted to concurrently move the various supporting members to release the various doors, means for locking a supporting member independently of the operating mechanism before said member is entirely released from the operating mechanism.
37. In a dump car, the combination of a plurality of dumping doors, a plurality of movable supporting members therefor, operating mechanism adapted to concurrently move the various supporting members to release the various doors, means for locking any supporting member independently of the others and independently of the operating mechanism when moved, and means whereby the operating mechanism holds the supporting members after they are locked until the operating mechanism is actuated.
- In testimony whereof, I hereunto affix my signature in the presence of two witnesses.

JOSEPH R. BOWLING.
